UNITED STATES PATENT OFFICE.

DONALD L. CAIN, OF OKOBONI, IOWA.

PLATE-HOLDER KIT.

1,065,504.

Specification of Letters Patent. Patented June 24, 1913.

Application filed August 24, 1912. Serial No. 716,873.

To all whom it may concern:

Be it known that I, DONALD L. CAIN, a citizen of the United States of America, residing at Okoboji, in the county of Dickinson, State of Iowa, have invented certain new and useful Improvements in Plate-Holder Kits, of which the following is a specification, reference being had therein to the accompanying drawing.

10 This invention relates to cameras and has special reference to a plate-holder kit therefor.

One object of the invention is to provide a simple form of plate-holder kit which may 15 be slipped into the ordinary plate holder for the purpose of allowing the use of a small size plate in a large camera.

With the above and other objects in view this invention consists in general of certain 20 novel constructions, combinations and arrangements of parts as will be hereinafter fully described, illustrated in the accompanying drawings, and specifically claimed.

In the accompanying drawings like characters of reference indicate like parts in the several views, and: Figure 1 is a front elevation of a plate-holder kit constructed in accordance with this invention. Fig. 2 is a rear elevation thereof. Fig. 3 is a section 25 on the line 3—3, of Fig. 1. Fig. 4 is a section on the line 4—4, Fig. 1. Fig. 5 is an end view thereof.

In the construction of this invention there are employed side bars 10 which are jointed 30 to an end bar 11 at one end and to an end

bar 12 at the other. The side bars 10 and end bars 11 are each provided with an overhanging strip 13 while the bar 12 is without any such strip. The ends of the strip 13 adjacent the bar 12 are flared as indicated 40 at 14 for the purpose of permitting the ready introduction of a plate.

In using the invention the plate-holder kit is slipped inside of the usual plate holder with the plate in position. The plate is 45 then used in the ordinary manner.

There has thus been provided a simple and efficient device of the kind described and for the purpose specified.

Having thus described the invention, what 50 is claimed as new, is:—

A plate-holder kit for cameras comprising a pair of spaced side bars, an end bar connecting the side bars at one end, overlapping strips projecting over the outer 55 edges of said bars and spaced from the inner edges, a second end bar connecting the remaining ends of the side bars, said strips having their inner edges adjacent the second bar flared for constituting a guiding 60 means for facilitating the insertion of a plate into the holder and for preventing the corners of the plate from becoming nicked during the insertion.

In testimony whereof I hereunto affix my 65 signature in presence of two witnesses.

DONALD L. CAIN.

Witnesses:

FRED JENSEN,
J. E. STEELE.
